UNITED STATES PATENT OFFICE.

GUSTAVE E. VILLARET, OF LEONIA, NEW JERSEY, ASSIGNOR TO OWEN WALSH M'F'G. CO., INC., OF NEW YORK, N. Y., A CORPORATION OF NEW YORK.

DESIGN FOR A BASE FOR A CHANDELIER.

Application filed April 11, 1927. Serial No. 21,539. Term of patent 3½ years.

To all whom it may concern:

Be it known that I, GUSTAVE E. VILLARET, a citizen of the United States, residing at Leonia, Bergen County, New Jersey, have invented a new, original, and ornamental Design for a Base for a Chandelier, of which the following is a specification, reference being had to the accompanying drawing, forming part thereof.

Fig. 1 is a bottom view of a base for a chandelier showing my new design, only a portion of the ornamentation being shown completed, the unornamented portion in-

volving a mere repetition of the completed portion;

Fig. 2 is a fragmentary elevational view taken substantially along the line 2—2 of Fig. 1; and

Fig. 3 is a fragmentary elevational view taken substantially along the line 3—3 of Fig. 1.

I claim as my invention:

The ornamental design for a base for a chandelier substantially as shown.

GUSTAVE E. VILLARET.
